AUTO CHIROPODIST

Filed Dec. 15, 1930

INVENTOR
HUGH R. BYNUM
by J. W. Weatherford
ATTORNEY.

UNITED STATES PATENT OFFICE

HUGH R. BYNUM, OF MEMPHIS, TENNESSEE

AUTO CHIROPODIST

Application filed December 15, 1930. Serial No. 502,332.

This invention relates to a device for the treatment of corns and callouses on the foot and is especially designed for individual use by those who through preference or otherwise, do their own treating, though it may also be used by chiropodists. It is primarily a holder or handle adapted to receive and secure for use a sheet of sand paper or the like abrasive. The invention relates further to the cross sectional shape of the holder by means of which abrasive surfaces of a plurality of curvatures are provided, which variously curved surfaces adapt the device particularly to the uses for which it is primarily designed.

In the practice of chiropody and especially in that part of it which relates to removal of corns and callouses from the feet, the chiropodist ordinarily employs a sharp knife with which these accretions or growths are removed. In most cases however this work may quite as readily be accomplished by the use of an abrasive, and in the interest of sanitation and asepsis a surface covered with a sheet of abrasive material which may be used and thrown away is inherently of great value.

The objects of the present invention are:—

(a) To provide a holder for a sheet of abrasive material which will secure and stretch the sheet tight;

(b) To provide readily releasable means for securing the sheet material to the holder;

(c) To provide an abrasive tool having three or more surfaces of different curvatures; and

(d) To generally improve the design and construction of the holder for sheets of abrasive material.

The means by which the foregoing and other objects are accomplished and the manner of their accomplishment will readily be understood from the following specification on reference to the accompanying drawings, in which:

45 Fig. 1 is a side elevation of the device;

Fig. 2 is a section on the line II—II of Fig. 1, looking in the direction of the arrow;

50 Fig. 3 is a view taken at the same place looking in the same direction showing the

holder opened up with a sheet of abrasive material partially secured thereto;

Fig. 4 is a sectional end elevation taken on the line IV—IV of Fig. 1, looking in the direction of the arrow; and

55

Fig. 5 is a reduced scale view showing the shape and method of folding the sheet of abrasive used.

Referring now to the drawings in which the various parts are indicated by numerals, 60 10 is a holder for a sheet of abrasive material 11, such as sand paper, and 12 is a handle for the device. The holder comprises two elongated parts 13 and 14 respectively which are connected along one edge by a hinge 15. 65 These parts are preferably made of sheet material and closed at both ends by heads 16 and 17, respectively. The sheet of abrasive material 11 is disposed around the exterior surface of these parts and is secured to them by 70 folding strips 18 and 19 at opposite sides of the sheet, over the edges of the parts 13 and 14, so that the strip 18 lies within the part 13, and the strip 19 within the part 14. These strips are held respectively by clamps 20, 21. 75 The clamp 20 is hinged on a pin 22 and the clamp 21 on a pin 23 which pins are secured in the heads 16 and 17 respectively. The clamp 20 and 21 are held against the strips 18 and 19 by springs 24 and 25 respectively. 80 26 is a spring for opening the parts of the holder when it is desired to remove or replace the abrasive material.

Secured to each of the ends 16 as by the screws 27 are flat springs 28 each of which 85 carries a lug 29 adapted to engage a notch or hole 30 in an end 17 of the opposite part when the two parts are closed together as shown in Figs. 2 and 4. Each of the springs has a button 31 which projects therefrom through 90 the end, whereby the springs may be depressed to disengage the lugs 29 from the holes 30 and release the holder parts.

When the holder is closed as shown in the cross section Fig. 4, it presents three principal curved surfaces A, B, and C, which have radii increasing in the order named so that these surfaces are of varying curvature. In addition the surfaces A and B; B and C; and C and D are respectively connected by sur- 100

faces of different curvatures so that three primary surfaces and three secondary surfaces are provided.

To prepare the holder for use the buttons 31 are depressed disengaging the lugs 29 and permitting the parts of the holder to be swung open by the spring 26. A sheet of abrasive material 11, ordinarily sand paper, having folded edges 18 and 19 is engaged 5 with the folded strip 18 at one edge secured by the clamp 20 and the opposite folded strip 19 is brought over the edge of the opposite part 14 and secured by the clamp 21. These clamps may be swung away from their respective holder parts as indicated in Fig. 3, 10 by the dotted position 21A of the clamp, in order to permit placing of the abrasive material. The parts 13 and 14 are then closed around the hinge 15 until the lugs 29 snap 15 into the openings 30 at which time if the sheet of abrasive material be properly sized and folded it will be tightly drawn over the outer surface of the holder. It is proposed 20 to cut the sheets of material 11 to proper size, to cut away the corners 32 and fold the edges 25 along definite parallel lines 33, as shown in Fig. 5, so that the sheet will properly fit the holder and so that when assembled thereon it will be tightly drawn over the surface 30 thereof.

Having described my invention, what I claim is:

1. An abrasive tool, comprising supplementary elongated hollow parts, hinged together along one longitudinal edge of each, a sheet of abrasive material having a main portion coextensive with the external surface of said parts, and having integral inwardly folded strips along the side edges of 35 said sheet engaging over the unhinged edges of said parts, clamps within said hollow parts, hinged one to each of said parts and respectively engaging each an inwardly folded strip, means resiliently urging said clamps 40 against said strips, and releasable means for holding the unhinged edges of said parts together.

2. An abrasive tool, comprising a pair of elongated hollow parts, hinged together along one longitudinal edge of each, a sheet of abrasive material having a main portion coextensive with the external surface of said parts, and having integral inwardly folded strips along the side edges of said sheet engaging over the unhinged edges of parts, 50 clamps, disposed within said hollow parts, hinged one to each of said parts and respectively engaging each an inwardly folded strip, springs each holding a clamp in engagement with a strip, and releasable means for holding the unhinged edges of said parts together.

3. An abrasive holder, comprising an elongated structure presenting a cross section embracing three arcs of varying radii, said arcs

being connected by arcs of smaller radii, and which latter arcs are of unequal radii.

4. An abrasive holder, comprising an elongated structure presenting a cross section embracing three or more arcs of varying radii, 70 said arcs being connected by arcs of smaller radii.

In testimony whereof I hereunto affix my signature.
